UNITED STATES PATENT OFFICE

CHESTER A. FRICK, OF MUNCIE, INDIANA, ASSIGNOR TO GLASCOCK BROTHERS MFG. COMPANY, OF MUNCIE, INDIANA, A CORPORATION OF INDIANA

BOTTLE COOLING BOX

Application filed January 23, 1928. Serial No. 248,699.

My invention relates to an improvement in refrigerators for bottled goods and has particular reference to that type of refrigerator wherein the bottles are fed through the refrigerator through U shaped channel-ways, being emersed while maintained in the channel-ways in a refrigerating fluid.

It is one of the objects of my invention to provide a refrigerator of the above type wherein with the minimum floor space a refrigerator may be constructed to receive a maximum number of bottles and to receive and handle bottles of various types and dimensions.

15 It is a further object of my invention to provide a refrigerator of the above type in which the passageways for the bottles are readily accessible for the purpose of cleaning, etc., and in which the cooling fluid level may 20 be maintained at a predetermined point, which is normally higher than the liquid level in the refrigerant container.

For the purpose of disclosing my invention I have illustrated one embodiment of the 25 same in the accompanying drawings, in which—

Fig. 1 is a front elevation of a refrigerator embodying my invention;

Fig. 2 is a side elevation thereof;

30 Fig. 3 is a sectional view taken on the line 3—3 of Fig. 2;

Fig. 4 is a sectional view taken on the line 4—4 of Fig. 1;

Fig. 5 is a longitudinal sectional view;

35 Fig. 6 is an enlarged section of one of the bottle channels;

Fig. 7 is a partial perspective view of the ends of the bottle channels;

Fig. 8 is a detail section of the drain and 40 overflow connection;

Fig. 9 is a detail section on the line 9—9 of Fig. 1;

Fig. 10 is a detail section on the line 10—10 of Fig. 1;

45 Fig. 11 is a bottom plan;

Fig. 12 is a detail section on the line 12—12 of Fig. 1;

Fig. 13 is a section on the line 13—13 of Fig. 12;

50 Fig. 14 is a perspective view showing the

manner of securing the castors for the box in position;

Fig. 15 is a detail perspective showing the manner of interlocking the two sections of the liner;

Fig. 16 is a detail section through one edge of the cover, and

Fig. 17 is a detail section showing the manner of supporting the hub frame.

In carrying out my invention I provide an outer enclosing casing consisting of the four corner posts 1 between which are secured the panels 2. The corner posts 1 preferably consist of angle members, the ends of which are provided with inturned flanges 3 which abut against inturned flanges 4 at the vertical edges of the panels, the panels and corner posts being secured together by suitable bolts 5 passing through these abutting flanges. The bottom edges of each of the panels are turned inward to form flanges 6 which meet with similar inturned flanges 7 on the bottom corner members 8 being held together by bolts 9 and the bottom plate 10 is supported on the horizontal legs of the angles 8. The casing thus formed is lined on its sides and bottom with a suitable insulating material 11 preferably in the form of cork slabs.

A rectangular frame is mounted within the casing at the top and is preferably formed of front and back rails 12 and end rails 13 constructed of U shaped channels suitably welded together at their joints to provide a rigid structure. For supporting this frame in position the corner posts 1 and panels 2 are slit for a short distance down from the top at the point where the flanges 3 and 4 are turned in and these flanges are turned down horizontally as at 3a and 4a to form supports for its frame. Supported within the casing is a U shaped corrugated outer tub 14, the upper edges 15 of which are welded to the two end rails 13. The two ends 16 of the tub are preferably flat and constitute the front and rear of the tub, the corrugations extending transversely of the tub. Co-operating with the outer tub to form channel members for the guidance of the bottles through the refrigerator, are a plurality of channelled necks 17, one for each corrugation. These

- necks are substantially semi-circular at their upper ends and merge into the substantially rectangular at their lower ends to provide side portions 18. As each neck coincides with 5 a corrugation of the tub a substantially cylindrical inlet is provided at the upper end of the tub, this inlet being round and forming an inlet guide, on one side and an outlet on the other side for the bottle. It will be 10 noted that the flattened sides 18 are opposite the "edges" of the corrugations, which corrugations are not in themselves sufficiently deep to permit the sides thereof to extend up around a bottle. In order therefore to increase 15 the depth of the channels I provide a series of flat ribs 19, the ends of which are welded or otherwise secured to the ends of the flat portions 18. These ribs form parts of the bottle channels to assist in the guiding of the bottles in their passage through the refrigerator. The ribs, therefore, together with the corrugations in the outer tub, provide a series of channels, U shaped in formation. It will be noted that the neck member 20 25 17, together with the corrugations form, at each end of the channel, substantially closed portions and this portion of the U shaped channels is substantially straight. This closed portion, however, widens toward its bottom so that at the point at about which the curvature of the leg of the channel commences, the channel is wider than at its top. 30 A U shaped liner rests on top of the ribs 19, being preferably formed in two sections 35 20 and 21, the upper edges of each of which take under lips 22 extending from the neck member 17 and the two sections at their bottoms being connected by a suitable latching mechanism 23. 40 The neck members 17 at their upper ends are each welded to a cross rail 24 which extends between the two end rails 13 and where they abut are likewise welded together so that a stiff rigid structure is thus provided. 45 The structure thus far described provides a series of U shaped channels, the legs of the U being substantially straight and contracting toward the ends, the channels all having liquid communication with one another. 50 Within the channel structure as above formed, is mounted a refrigerant containing tub 25 which is preferably U shaped in form and has its upper edge provided with an outwardly flaring lip 26 resting on shoulders 55 27 extending from the upper frame work. These same shoulders provide supports for a closure member 29 or cover, which closes the icing opening. This tub near its top is provided with overflow openings 30 which communicate with the channelled liquid container and the tub is held in position by a suitable latch or bolt 31. By the provision of this tub a relatively high water level may be maintained in the bottle-receiving compartments. It is to be noticed that, due to the

construction of the bottle-receiving channels, the cooling liquid can not be confined within these channels as has been the case in certain boxes of this type heretofore constructed and therefore the water level in the portion adapted to receive the ice, if it were not for the inner tub, would be very high. By the provision, however, of the inner tub, which is removable, the water level exterior of this tub may be maintained at a relatively high 70 level while comparatively little water is in the ice tub itself. It has been found that where the ice tub is used a much more efficient cooling of the bottles is obtained than would be the case if the ice tub were dispensed with 75 and the entire interior of the structure filled with water, to maintain a high water level, with the ice in the water. I am thus able to maintain the high water level desirable in such structures as for instance as shown in 80 my former Patent No. 1,631,091, dated May 31, 1927, and at the same time provide a means whereby the bottle-receiving channels may be readily cleansed. 85

The top of the structure is suitably covered by cover plates 32 which are provided with doors 33, normally closing the entries and exits of the bottle-receiving channels. Bolts or screws 32a passing through the down turned flange of the top 32 and through the 90 corner posts 1 and the channel members of the frame aid in holding the top plate in position and prevent vertical displacement of the frame. The entry side of these channels is provided with spring plungers 34 which 95 project into the path of the bottle to such an extent that a bottle can not be inserted bottom first, although when the bottle is inserted neck first the tapering portion of the neck will act as a cam to move the spring 100 plungers to one side. 105

The closure 29 preferably consists of top and bottom plates 35 and 36 between which is located suitable insulating material 37, such for instance as cork or the like. The 110 top plate 35 at its edges is turned downwardly and this downturned portion is connected with the bottom plate 36 by a Z shaped channel 38, the center horizontal leg of which has lips 39 struck up, which lips engage over the flattened portion 40 of a sealing bead 41. This bead extends around on the four sides of the cover and when the cover is placed in position provides an effective air tight seal to the interior of the refrigerator. 115 120

The corner posts 1 are extended beyond the bottom of the casing to provide legs 42 which are squared and braced by angles 43 welded or otherwise secured to the in-turned lips 3. These angles 43 have side wings 44 widened at their tops and provided with inturned substantially horizontal wings 45 which are welded to the diagonally extending channel braces 46 thrown across the bottom of the structure. This arrange- 125 130

ment provides for a rigid bracing of the legs of the structure and in event it is desired that castors may be placed so that the box may be readily moved the diagonal braces 46 are notched as at 47 to receive a plate 48 the ends of which are turned up at 49 and are secured to the side walls of the channels 46 by bolts 50, which extend therethrough. The castors 51 may be bolted or welded to the plates 48.

In practice the water level is maintained in the channelled tub at a relatively high point, the tub having no overflow drain except through the openings 30 into the refrigerant containing tub 25. In order that overflow drainage may be maintained in the refrigerant containing tub 25 and in order that, when desired, the cooling liquid in the channelled tub may be drained off, I provide a drain of the type illustrated in Fig. 8. In this figure it will be seen that the tub 25 drains through a drainage member comprising an elbow 52 between the inner wall of which and a clamping screw 53 the wall 23 of the tub is clamped, the clamping screw having a drain opening 54 therein. This elbow 52 is connected by the piping 55 with a fixture having an extension 56, passing through one of the end walls 16 of the outer tub which extension is normally closed by a plug 57. The fixture however is provided with a by-pass opening 58 whereby the overflow through the pipe 55 may pass around the plug 57 and this fixture at its bottom end is provided with a drain extension 59 having an outer screw-threaded nipple 60. This nipple projects downwardly through the bottom of the casing. A second drain extension 61 projects through the side of the casing and is provided with a threaded nipple 62. The threaded nipples 60 and 62 have the same number of threads and are of the same size so that a cap 63 may be used to close either one, the arrangement being such that, if desired, the nipple 60 may be connected to a stationary drain pipe or, if this is inconvenient, this nipple 60 may be closed by the cap 63 and the drain pipe or a drainage hose connected with the nipple 62. The above arrangement provides for a constant drainage through the opening 54 of the inner tub, while permitting a drainage when desired, from the outer tub. It will be noted that the drain opening 54 is considerably below the openings 30 so that while a high water level is maintained in the channelled tub a comparatively low water level is maintained in the refrigerant container.

I claim as my invention:

1. In a device of the character described the combination with a U shaped transversely corrugated tub, of substantially arcuate guides co-operating with said corrugations adjacent the edges of said tub to form tubular passageways at the exit and

entering ends of said tub and fins cooperating edgewise with the ridges of said corrugations to increase the depth thereof.

2. In a device of the character described the combination with a U shaped tub transversely corrugated, the legs of the U being substantially vertical, of guides arcuate in cross section co-operating with the substantially vertical corrugations to form tubular channels, said channels increasing in cross sectional area toward the bottom of the tub.

3. A refrigerator comprising a substantially U shaped tub having channel-ways formed therein, a plurality of guideways arcuate in cross section co-operating with the vertical legs of the channel-ways to form tubular channels, fins co-operating with said channel-ways in the bight of the tub and having their inner edges arcuate, and a cover plate for said channel-ways in the bight of the tub resting on said arcuate fins.

4. A refrigerator comprising a substantially U shaped tub having channel-ways formed therein, said tub being closed to maintain a water level adjacent the top thereof and a removable refrigerant container mounted in said tub having a drain opening for maintaining a water level at a point considerably lower than the water level maintained in said channelled tub.

5. A refrigerator comprising a casing having a horizontal frame at its top, a channelled U shaped tub arranged within said casing and supported from members of said frame, guide-ways arcuate in cross section supported from other members of said frame adjacent said channel-ways to co-operate therewith to form tubular channels, said guideways at their bottoms being substantially rectangular, and arcuate channel fins having their ends secured to the side walls of said guide-ways and supported thereby.

6. A refrigerator comprising a casing having a horizontal frame at its top, a channelled U shaped tub arranged within said casing and supported from members of said frame, guide-ways arcuate in cross section supported from other members of said frame adjacent said channel-ways to co-operate therewith to form tubular channels, said arcuate guide-ways at their bottoms being substantially rectangular, arcuate channel fins having their ends secured to the side walls of said guide-ways and supported thereby, and a cover plate supported on said arcuate fins.

7. A refrigerator comprising an outer U shaped transversely corrugated tub, a plurality of arcuate fins and a cover plate mounted on said fins forming an inner channelled member co-operating with the corrugations of the outer tub to form tubular channels.

8. A refrigerator comprising an outer U shaped tub having channel-ways formed therein, a plurality of arcuate fins spaced

apart from said outer tub and a cover plate mounted on said arcuate fins and forming therewith an inner channelled member co-operating with said outer tub to form tubular liquid communication channels.

5 In witness whereof, I, CHESTER A. FRICK, have hereunto set my hand at Muncie, Indiana, this 10th day of January, A. D. one thousand nine hundred and twenty-eight.

10 CHESTER A. FRICK.
